Philip T. Sawyer, New York

UNITED STATES PATENT OFFICE.

PHILIP A. REUTTER, OF WATERBURY, CONNECTICUT, ASSIGNOR TO SCOVILL MANUFACTURING COMPANY, OF WATERBURY, CONNECTICUT, A CORPORATION OF CONNECTICUT.

SPRING CATCH FOR VANITY BOXES.

Application filed May 21, 1928. Serial No. 279,416.

This invention relates to certain improvements in vanity boxes or cases.

These vanity boxes or cases which have now come into wide use for holding powder and like cosmetics usually include a body and a cover pivotally associated on a hinge, and in most instances also include a mirror, and spring catches are commonly employed for holding the body and the cover together. These boxes are made usually of light metal and it is desirable that the parts of the box be so formed and arranged that they can be cheaply made and rapidly assembled.

It is the especial object of the present invention to provide an improved construction for securing a mirror or other toilet article in the box, the securing means also acting to securely position a spring catch, means being provided for limiting the movement of the catch so that it cannot become displaced when manipulating to open the box.

With this and other objects not specifically referred to in view, the invention consists in certain novel parts, arrangements and combinations which will be described in connection with the accompanying drawings and the novel features pointed out in the claims hereunto annexed.

In these drawings, which illustrate a preferred form of the invention,—

Figure 1 is an edge view of the improved box;

Figure 2 is a face view of the box when open;

Figure 3 is a detail sectional view, on an enlarged scale, looking in the direction of arrow 3 of Figure 2, and

Figure 4 is a detail sectional view looking in the direction of arrow 4 of Figure 2.

Referring now to these drawings, the vanity case which has been selected to illustrate the invention is of light metal and is of the so-called knife edge type and includes a body 1 and a cover 2 pivotally united on a hinge 3 of any suitable or desired type. The body 1 is capacitated to receive a toilet article such as a compact 4 held in position by a retaining wire 5. The cover 2 is also capacitated to receive a toilet article, the article held in the cover being in the present instance a mirror, indicated by the numeral 6.

The body and the cover are secured to-

gether by an improved spring catch construction and, in accordance with the present invention, an improved means is provided for holding the mirror and the catch in position so that the catch is securely held and cannot become displaced when the box is opened. While the particular form of catch may be somewhat varied and may be held in place in different ways, in a box embodying the invention in its best form there will be provided a bezel 7 which is in the form of a flat ring of light metal having a central aperture. This bezel is dimensioned so as to snugly engage the wall 8 of the box and is provided with a cut out portion 9, at the ends of which are shoulders 10, 11. This bezel is forced into position on the mirror 6 and thus firmly holds the mirror in position. If desired, a lining of paper or other suitable material 12 may be placed in the cover below the mirror and, as shown, the mirror is of less diameter than the cover of the box, the edges of the bezel overlying the mirror, the mirror being visible through the central aperture of the bezel.

Located in the cut out portion is a spring catch which may be of various constructions, but which is held in position by the bezel so that soldering or riveting is unnecessary. As illustrated, this catch is in the form of a flat strip of spring metal 13 which is slightly shorter than the cutout 9. This spring strip is provided with a catch 14, formed by turning over the metal of the strip, and with an integral manual release 15, formed by bending the metal of the strip at right angles, these parts extending outwardly through openings 16, 17 formed in the wall of the box. The strip is also formed with an inwardly extending part arranged to lie under the bezel and which acts to prevent the strip from moving upwardly out of the cut out portion. In the particular construction shown, this inwardly projecting part is shown as a pair of feet 18, 19 formed at each end of the strip by bending the metal of the strip inwardly at right angles.

With the construction shown and described it will be seen that the spring is securely held by the bezel and prevented from upward displacement by the feet 18, 19. On the manipulation of the manual release inwardly to free catch 14, the ends of

the strip engage the shoulders 10, 11 and thus prevent the spring strip from being pushed inwardly too far. Thus the strip is securely held in position both in the open and closed positions of the box and during the manipulation of the catch.

While the invention has been shown and described in its preferred form, it will be understood that certain changes and variations may be made in the specific construction shown and described without departing from the invention as defined in the appended claims.

What I claim is:

15. 1. In a vanity case, a body, a cover, a hinge pivotally associating these parts, a toilet article in one of the parts, a bezel holding the article in place, shoulders formed on the bezel, a spring strip having a catch for holding the body and cover together and a manual release, said strip having a part engaged beneath the bezel by which the strip is held in position, the ends of the strip lying between the shoulders of the bezel.
20. 2. In a vanity case, a body, a cover, a hinge pivotally associating these parts, a mirror in one of the parts, a bezel holding the article in place and having a cutout, and a spring catch positioned in the cutout and having projections extending inwardly under the bezel, said strip lying in the cutout of the bezel and between the shoulders.
25. 3. In a vanity case, a body, a cover, a hinge pivotally uniting these parts, a toilet article in one of the sections, a bezel holding the article in place and having a cutout, and a spring strip having catch means for holding the body and cover together, said strip having an integral outwardly extending manual release, and integral feet inwardly extending under the bezel, said strip lying in the cutout of the bezel and between the shoulders.

mirror in place, shoulders formed on the bezel, a spring strip having a catch for holding the body and cover together and a manual release, said strip having feet extending inwardly under the bezel by which the strip is held in position, the ends of the strip lying between the shoulders of the bezel.

30. 3. In a vanity case, a body, a cover, a hinge pivotally uniting these parts, a mirror in one of the parts, a bezel having a cut out portion forming shoulders, and a spring strip having catch means for holding the body and cover together, said strip having an integral outwardly extending manual release, and integral feet inwardly extending under the bezel, said strip lying in the cutout of the bezel and between the shoulders.

35. 4. In a vanity case, a body, a cover, a hinge pivotally uniting these parts, a toilet article in one of the sections, a bezel holding the article in place and having a cutout, and a spring catch positioned in the cutout and having projections extending inwardly under the bezel.

40. 5. In a vanity case, a body, a cover, a hinge pivotally uniting these parts, a toilet article in one of the sections, a bezel holding the article in place and having a cutout, and a spring catch positioned in the cutout and having projections extending inwardly under the bezel.

45. 6. In a vanity case, a body, a cover, a hinge pivotally uniting these parts, a toilet article in one of the sections, a bezel holding the article in place and having a cutout, and a spring catch positioned in the cutout and having projections extending inwardly under the bezel.

50. 7. In a vanity case, a body, a cover, a hinge pivotally uniting these parts, a toilet article in one of the sections, a bezel holding the article in place and having a cutout, and a spring catch positioned in the cutout and having projections extending inwardly under the bezel.

55. 8. In a vanity case, a body, a cover, a hinge pivotally uniting these parts, a toilet article in one of the sections, a bezel holding the article in place and having a cutout, and a spring catch positioned in the cutout and having projections extending inwardly under the bezel.

60. 9. In a vanity case, a body, a cover, a hinge pivotally uniting these parts, a toilet article in one of the sections, a bezel holding the article in place and having a cutout, and a spring catch positioned in the cutout and having projections extending inwardly under the bezel.

65. 10. In a vanity case, a body, a cover, a hinge pivotally uniting these parts, a toilet article in one of the sections, a bezel holding the article in place and having a cutout, and a spring catch positioned in the cutout and having projections extending inwardly under the bezel.

70. 11. In a vanity case, a body, a cover, a hinge pivotally uniting these parts, a toilet article in one of the sections, a bezel holding the article in place and having a cutout, and a spring catch positioned in the cutout and having projections extending inwardly under the bezel.

75. 12. In a vanity case, a body, a cover, a hinge pivotally uniting these parts, a toilet article in one of the sections, a bezel holding the article in place and having a cutout, and a spring catch positioned in the cutout and having projections extending inwardly under the bezel.

80. 13. In a vanity case, a body, a cover, a hinge pivotally uniting these parts, a toilet article in one of the sections, a bezel holding the article in place and having a cutout, and a spring catch positioned in the cutout and having projections extending inwardly under the bezel.

85. 14. In a vanity case, a body, a cover, a hinge pivotally uniting these parts, a toilet article in one of the sections, a bezel holding the article in place and having a cutout, and a spring catch positioned in the cutout and having projections extending inwardly under the bezel.

90. 15. In a vanity case, a body, a cover, a hinge pivotally uniting these parts, a toilet article in one of the sections, a bezel holding the article in place and having a cutout, and a spring catch positioned in the cutout and having projections extending inwardly under the bezel.

95. 16. In a vanity case, a body, a cover, a hinge pivotally uniting these parts, a toilet article in one of the sections, a bezel holding the article in place and having a cutout, and a spring catch positioned in the cutout and having projections extending inwardly under the bezel.

PHILIP A. REUTTER.
